JOHN T. WEBSTER, OF NEW YORK, N. Y., ASSIGNOR TO DANIEL M. READ
AND CHARLES A. READ, OF BRIDGEPORT, CONNECTICUT.

Design No. 4,717, dated March 14, 1871.

DESIGN FOR A CARPET-PATTERN.

The Schedule referred to in these Letters Patent and making part of the same.

To all whom it may concern:

Be it known that I, JOHN T. WEBSTER, of the city of New York, in the county and State of New York, have invented a new and original Design for a Carpet; and I do hereby declare that the following is a full, clear, and exact description thereof, which will enable others skilled in the art to make and use the same, reference being had to the accompanying photographic illustrations forming part of this specification.

The nature of my invention is fully represented in the accompanying photographic illustrations, to which reference is made.

I claim as my invention—
The design for a carpet, as shown.

JOHN T. WEBSTER.
